PHASE-CORRECTING LOW-PASS FILTER

Harold A. Wheeler, Great Neck, N. Y., assignor to
Hazeltine Corporation, a corporation of Delaware

Application May 18, 1938, Serial No. 208,513

12 Claims. (Cl. 178—44)

This invention relates generally to low-pass wave-filter circuits and particularly to a low-pass filter section utilized as a phase-linear filter, as a phase-correcting section in a confluent network, 5 or as a phase-correcting filter co-operating with other filters having phase distortion.

In many electrical circuits it is desirable to translate signals of a wide range of frequencies through an electrical network with a predetermined frequency phase-shift characteristic or, in the case of distortionless transmission, with a phase shift in the network directly proportional to the frequency. For instance, in the translation and amplification of a video-frequency signal in 10 a television apparatus, it is required to translate signals comprising a wide band of frequencies and including frequencies very low as compared with the cutoff frequency. The circuits have the characteristics of low-pass filters, even though they 15 do not pass signals quite down to zero frequency. While it is desired to translate such signals with no distortion in any stage of the signal-translating channel, this may not be practicable so that it may be necessary to provide phase-correcting 20 circuits in the signal-translating channel. Such phase-correcting circuits may be utilized for the purpose of providing a distortionless over-all characteristic for the signal-translating channel or for providing a given frequency phase-shift 25 characteristic for one part of the signal-translating channel which is complementary to such characteristic of some other part of the channel.

Certain phase-correcting networks have heretofore been utilized for the purpose discussed 30 above. In designing a phase-correcting section for a particular form of correction, it is necessary to select a type of filter section whose phase shift varies in the desired manner over the entire pass band of the system in which it is to be utilized. 35 It is highly desirable, therefore, to have available a phase-correcting network whose phase shift can be given the desired value at one or more frequencies within the pass band. In practice, such phase-correcting filters are usually designed 40 to have a phase shift which is a multiple of π at one or more predetermined critical frequencies within the pass band. Those phase-correcting filter sections of the prior art which have such a characteristic require a relatively large coefficient 45 of inductive coupling between inductances in the filter section and, furthermore, such prior art filter sections do not tolerate a shunt capacitance of any appreciable magnitude across the terminals of the section. The normal characteristics 50 of such filters are disturbed by any inherent

capacitance of the circuit elements connected across the terminals at either end of the phase-correcting section.

Also, since the requirement for distortionless transmission over a band of frequencies is a straight-line frequency phase-shift characteristic for the network, it is particularly desirable to obtain in a low-pass network having generally the desired characteristic, a phase-correcting section capable of further correcting the phase shift of the system to its theoretically correct value at one or more points in the pass band. With a plurality of such phase-correcting networks, any desired degree of correction of the over-all transmission characteristic of the system is possible. 15

It is an object of the invention, therefore, to provide an improved low-pass phase-correcting network for use in a filter system, the phase shift of which can be predetermined as desired at one or more frequencies within the pass band. 20

It is another object of the invention to provide an improved low-pass filter for substantially distortionless transmission of a wide band of frequencies, the frequency phase-shift characteristic of which passes through a straight line through 25 the origin at several points in the pass band, one of the points being the origin.

It is another object of the invention to provide a phase-correcting filter section for the purposes described above which includes substantial shunt 30 capacitance across either or both terminals.

It is still another object of the invention to provide a phase-correcting filter section of the type described requiring a relatively small coefficient of inductive coupling between inductance 35 elements of the filter circuit.

In accordance with one embodiment of the invention, there is provided a low-pass filter section comprising a transformer, the windings of which are connected as series arms of a ladder 40 network whose shunt arms comprise capacitance elements. Input and output terminals of the section are across the terminal shunt capacitance elements. The reactive elements of the section are so proportioned as to provide a low-pass filter 45 circuit having constant- k mid-shunt image impedance at each end, a predetermined cutoff frequency, and a phase shift which is a multiple of π at selected critical frequencies within the pass band. In other words, the frequency phase-shift 50 characteristic of the filter section of this embodiment of the invention can be utilized, in a low-pass signal-translating channel, to compensate for the usual forms of phase distortion over the major part of the pass band. 55

In another embodiment of the invention there is provided a filter section comprising three or more inductance elements inductively coupled in pairs, the individual elements being connected in the series arms of a ladder network, the shunt arms of which are capacitance elements. The reactive elements of the circuit are so proportioned as to provide a low-pass filter circuit having constant- k mid-shunt image impedance at each end, a predetermined cutoff frequency, and a phase shift which is a multiple of π at two or more independent selected critical frequencies within the pass band. In other words, the frequency phase-shift characteristic of this embodiment of the invention can be utilized in a system to provide a greater degree of phase correction. In a variation of this embodiment of the invention, the three above-mentioned inductance elements are bridged by an additional inductance element. This bridged ladder circuit has the advantage that a complete freedom of choice of critical frequencies is procured in a symmetrical filter section with only one inductive coupling.

For a better understanding of the invention, together with other and further objects thereof, reference is had to the following description taken in connection with the accompanying drawing and its scope will be pointed out in the appended claims.

Referring now to the drawing, Fig. 1a is a circuit diagram of the filter composition of one embodiment of the invention and is utilized to explain the general theory of the invention; Figs. 1b and 1d are circuit diagrams of ladder networks utilized, respectively, to obtain one-point and two-point phase correction within the pass band; Fig. 1c is a graph illustrating certain operating characteristics of the circuits of Figs. 1a and 1b; Fig. 2a is a circuit diagram of a network providing phase correction at two predetermined frequencies within the pass band; Fig. 2b is a graph illustrating an operating characteristic of the circuit of Fig. 2a; Fig. 3a is a combination of the circuits of Figs. 1d and 2a; Fig. 3b is a modification of the circuit of Fig. 3a with self-inductances substituted for mutual inductances; and Fig. 4 is a circuit diagram of a vacuum-tube amplifier utilizing a phase-correcting filter in accordance with the invention.

Referring now more particularly to Fig. 1a, there is shown a phase-correcting network comprising an m -derived filter section interposed between two constant- k half-sections so that the image impedances of the network are those of mid-shunt terminations of a constant- k filter. The terminating impedances or resistors to which the input and output pairs of terminals of the circuit of Fig. 1a are coupled are represented by resistors R , R shown in dotted lines. The inductance of the shunt arm of the m -type section, in this case the filter having an m greater than unity, is negative. It is not possible, therefore, to construct this inductance as a separate element. However, in the circuit of Fig. 1b there is shown an equivalent network utilizing a transformer as an equivalent to the three inductance elements of the circuit of Fig. 1a. This network comprises inductances L , L having a coefficient of coupling k therebetween and connected in the series arms of a ladder network having shunt arms comprising condensers C_1 , C_1 connected across the terminal circuits thereof, and shunt arm C_2 interposed between inductances L , L .

Fig. 1c shows the frequency phase-shift characteristic of the circuits of Fig. 1a and Fig. 1b.

The shape of the phase characteristic may be determined by the choice of the value of m in the formulae hereinafter given. In other words, the intersection of each curve with the π phase-shaft line occurs at frequency f_1 , f_2 being the cutoff frequency, and x_1 being determined by the first of the following formulae which are applicable to the circuits of Figs. 1a and 1b:

$$x_1 = \frac{f_1}{f_2} = \frac{1}{\sqrt{1+m}}; m = \frac{1}{x_1^2} - 1 \quad (1) \quad 10$$

$$C_1 = \frac{1}{\omega_2 R}; R = \frac{1}{\omega_1 C_1} \quad (2)$$

$$C_2 = 2mC_1 = 2\left(\frac{1}{x_1^2} - 1\right)C_1 \quad (3) \quad 15$$

$$L = \frac{(1+m)^2}{\omega_2^2 C_2} = \frac{2}{x_1^4 \omega_2^2 C_2} \quad (4)$$

$$K = -\frac{m-1}{m+1} = -(1-2x_1^2) = \frac{M}{L} \quad (5) \quad 20$$

where ω_1 is the angular frequency corresponding to f_2 , and R is the image impedance at zero frequency. The value of m in the above equations may be determined from the curves of Fig. 1c. It will be seen that the curve $m=1$ is concave upwardly over the major portion of the pass band, while the curve $m=3$ is convex upwardly over the major portion of the pass band.

It will be seen from the above description and formulae that each of the circuits of Figs. 1a and 1b may be utilized as a phase-correcting filter network having a phase shift which is a multiple of π at one preselected critical frequency within the pass band and that such a filter presents a constant- k mid-shunt image impedance across each of its pairs of terminals.

The circuit of Fig. 1d is similar in some respects to the circuit of Fig. 1b and similar circuit elements have been given identical reference numerals in the two figures. The filter composition of the circuit of Fig. 1b is shown in Fig. 1a and comprises a single m -type section; the filter composition of the circuit of Fig. 1d is not shown but is similar except that it comprises two m -type sections. These may or may not have the same value of m . The circuit of Fig. 1d is effective to provide a phase shift which is a multiple of π at each of two critical frequencies in the pass band, while presenting a constant- k mid-shunt image impedance across each of its pairs of terminals. Formulae for the circuit of Fig. 1d may be derived on filter principles from the equivalent network comprising two m -derived sections.

The circuits described above illustrate the utility of the phase-correcting networks of the invention in securing a linear frequency phase-shift characteristic or for partially compensating for the curvatures of the characteristics of other networks to which the phase-correcting network is coupled. The same general utility is found in the circuits of Figs. 2a, 3a, and 3b, but these have greater freedom of design.

The circuit of Fig. 2a comprises inductors L_1 , L_2 and L_1 connected in the series arms of a ladder network and condensers C_3 , C_4 , C_4 , C_3 connected as shunt arms thereof. Pairs of input and output terminals are connected, respectively, across condensers C_3 , C_3 to which are coupled resistors R , R which may be actual terminating resistors or may represent the image impedances of the circuits to which the filter of the invention is coupled. Inductor L_5 is connected to bridge inductors L_1 , L_2 , L_1 while inductors L_1 , L_1 have

a coefficient of inductive coupling h_1 therebetween, as represented in the drawing by the dotted line M.

The following are the formulae applicable to the circuit of Fig. 2a:

$$k_1 = \frac{1-h_1^2}{1+h_1^2} \quad (6)$$

$$h_1^2 = \frac{f_4}{\sqrt{f_6^2 - f_5^2}} \quad (7)$$

$$C_3 = \frac{1}{R\omega_6} \quad (8)$$

$$C_4 = \frac{C_3(\omega_5^2 - \omega_4^2)}{\omega_4^2} \quad (9)$$

$$L_1 = \frac{1+h_1^2}{2C_3(\omega_5^2 - \omega_4^2)} \quad (10)$$

$$L_2 = \frac{4h_1^2 L_1}{2h_1^2 L_1 C_4 \omega_5^2 - h_1^2 - 1} \quad (11)$$

$$L_5 = \frac{4h_1^2 L_1}{2h_1^2 L_1 C_3(\omega_4^2 - \omega_5^2 + \omega_6^2) - h_1^2 - 1} \quad (12)$$

where the subscripts on the angular frequencies ω identify the angular frequencies with the corresponding frequencies f_4 , f_5 , and f_6 at which the filter has a phase shift of π , 2π , and 3π , respectively, f_6 being the cutoff frequency.

The circuit of Fig. 2a is thus effective to provide a phase-correcting circuit having a phase shift which is a multiple of π at each of two predetermined independent critical frequencies within the pass band and which presents a constant- k mid-shunt image impedance at its terminals. The frequency phase-shift characteristic of the circuit of Fig. 2a is represented by the graph of Fig. 2b.

The inductance L_5 as determined by Formula 12 becomes infinite, and may then be omitted from the circuit without altering its characteristics, if the following relation between the critical frequencies is satisfied:

$$(f_6^2 - f_5^2 + f_4^2) f_4^2 = (f_6^2 - f_5^2) (f_5^2 - f_4^2)^2 \quad (13)$$

The operation of the circuit thus modified is essentially unchanged except that the two critical frequencies within the pass band, at which the phase shift is a multiple of π , are interdependent.

Also, the circuit of Fig. 2a may be so proportioned as to secure a frequency phase-shift characteristic which is substantially linear over the major portion of the pass band. It is, however, impossible to provide a linear phase characteristic near the cutoff frequency. The maximum phase shift of the circuit of Fig. 2a is 3π , there being four critical frequencies as shown in Fig. 2b, these being f_3 , f_4 , f_5 , and f_6 . The critical frequencies may be so related that the curve between f_3 , or zero frequency, and f_5 is substantially linear by choosing equal frequency differences between successive critical frequencies except the last two and making the difference between the last two approximately half that between the other frequencies. These relationships are shown in the frequency phase-shift curve of Fig. 2b.

The general expression for the fraction A of the band having a linear frequency phase-shift characteristic, in a network of the type of the invention having a maximum phase shift $n\pi$ and having a number of critical frequencies equal to $(n+1)$, is:

$$A = \frac{2n-2}{2n-1} \quad (14)$$

The spacing of the critical frequencies in such a

design is uniform except that the space just inside the cutoff frequency is only one-half the uniform value.

In Fig. 3a there is shown a filter-correcting circuit in accordance with the invention which has the features of both Fig. 1d and Fig. 2a, similar circuit elements being given identical reference numerals. The only difference between the circuits of Figs. 2a and 3a is that there is, in the case of Fig. 3a, inductive coupling between the inductance L_2 and each of inductances L_1 , L_1 . It will be understood, however, that Equations 6-12, inclusive, given above as being applicable to Fig. 2a, are not applicable to the circuit of Fig. 3a inasmuch as they do not take into account the added mutual inductances. Comparable formulae may be derived utilizing well-known principles of filter design.

The circuit of Fig. 3b is the full equivalent of the circuit of Fig. 3a in which all the inductive elements are self-inductances. Similar circuit elements in the circuit of Fig. 3a and the circuit of Fig. 3b have been given identical reference numerals. L_3 , L_2 , L_1 , L_1 represent, respectively, the inductances L_1 , L_1 , L_2 less the mutual inductances. Additional self-inductances in the circuit of Fig. 3b have been added in place of mutual inductances in the circuit of Fig. 3a; thus, inductance element L_6 replaces the mutual inductance between inductance L_2 and one of inductances L_1 in Fig. 3a, and inductance L_7 replaces the mutual inductance between inductances L_1 , L_1 of Fig. 3a. Fig. 3b is given mainly for explanatory purposes, since one or more of L_6 , L_6 , L_7 would be negative in a phase-correcting filter, so that mutual inductance would be needed.

In Fig. 4 there is shown a filter in accordance with the invention which is utilized as a coupling circuit between the output electrodes of a vacuum tube 10 and the input electrodes of a vacuum tube 11. The inherent capacitance of the output circuit of vacuum tube 10 is represented by capacitance means 12 and 13 in parallel, while the inherent capacitance of the input circuit of vacuum tube 11 is represented by capacitance means 14 and 15 in parallel. These inherent capacitances tend to limit the response of the systems of the prior art as a wide band amplifier. A dead-end filter circuit comprising an inductance 16, condenser 17, and resistor 26 is coupled across capacitance 12, 13 to maintain a high impedance across the output terminals of vacuum tube 10 over a wide band of frequencies in a manner which is fully described in applicant's copending application, Serial No. 203,597, filed April 22, 1938. The filter circuit between the tubes 10 and 11, which is in all respects equivalent to the circuit of Fig. 1b, comprises inductances 18 and 19 which are widely separated from each other and adjacent, respectively, to vacuum tube 10 and vacuum tube 11. These inductances comprise series arms of the filter, being the equivalent of inductances L, L of the circuit of Fig. 1b. A shunt arm interposed between inductances 18 and 19, comprises a capacitance element 20 which takes the place of condenser C_2 of the circuit of Fig. 1b and may comprise at least partially the inherent capacitance to ground of inductances 18, 19, and 21 and associated circuit elements. Condensers C_1 , C_1 of Fig. 1b are replaced, respectively, by capacitance means 13 and 14. In order to provide a coupling between inductances 18 and 19 which is the equivalent of the mutual inductive coupling between inductances L, L of Fig. 1b, a link circuit is pro-

75

vided comprising an inductance 21 inductively coupled to inductance 18 and tapped on inductance 19. A grid-leak resistor 22 is provided for vacuum tube 11 while blocking condensers 23, 24 serve to confine direct currents to their proper paths.

In considering the operation of the circuit of Fig. 4, it will be seen that the dead-end filter, comprising capacitance elements 12 and 17, inductance 16, and resistor 26, serves to maintain a high value of impedance across the output circuit of vacuum tube 10 in a manner fully described in the above-mentioned copending application. The filter circuit of the present invention operates in the manner described in detail with respect to the circuit of Fig. 1b to provide a circuit in which a predetermined phase shift, equal to a selected multiple of π , is obtained at a selected critical frequency within the pass band of the system for any of the purposes outlined in detail above.

While there have been described what are at present considered to be the preferred embodiments of the invention, it will be obvious to those skilled in the art that various changes and modifications may be made therein without departing from the invention, and it is, therefore, aimed in the appended claims to cover all such changes and modifications as fall within the true spirit and scope of the invention.

30. What is claimed is:

1. A low-pass phase-correcting filter network for procuring a predetermined phase shift which is a multiple of π at each of one or more preselected frequencies within said band comprising, a ladder network including a plurality of inductances as series arms, at least one pair of said inductances having negative mutual inductance therebetween, a plurality of capacitance elements included as shunt arms, and input and output pairs of terminals across different ones of said shunt arms, the reactive constants of said filter network being so proportioned as to present constant- k mid-shunt image impedance across each of said pairs of terminals.

45. 2. A low-pass phase-correcting filter network for procuring a predetermined phase shift which is π at a preselected frequency within said band comprising, a ladder network including two negatively inductively coupled inductances as series arms, three capacitance elements as shunt arms, and input and output pairs of terminals across different ones of said shunt arms, the reactive constants of said filter network being so proportioned as to present constant- k mid-shunt image impedance across each of said pairs of terminals.

55. 3. A low-pass phase-correcting filter network for procuring a predetermined phase shift which is a multiple of π at each of two preselected frequencies within said band, comprising, a ladder network including two negatively inductively coupled inductances and a third inductance as series arms, four capacitance elements as shunt arms, and input and output pairs of terminals across different ones of said shunt arms, the reactive constants of said filter network being so proportioned as to provide constant- k mid-shunt image impedance across each of said pairs of terminals.

70. 4. A low-pass phase-correcting filter network for procuring a predetermined phase shift which is a multiple of π at each of two or more independent preselected frequencies within said band comprising, a ladder network including at least three inductances as series arms, at least one pair of said inductances having negative mutual

inductance therebetween, a plurality of capacitance elements as shunt arms, input and output pairs of terminals across different ones of said shunt arms, and an additional inductance connected to bridge said plurality of inductances, the reactive constants of said filter network being so proportioned as to provide constant- k mid-shunt image impedance across each of said pairs of terminals.

5. A low-pass phase-correcting filter network for procuring a predetermined phase shift which is a multiple of π at each of two independent preselected frequencies within said band comprising, a ladder network including three negatively inductively coupled inductances as series arms and four capacitance elements as shunt arms, input and output pairs of terminals across different ones of said shunt arms, and an additional inductance connected to bridge said three inductances, the reactive constants of said filter network being so proportioned as to provide constant- k mid-shunt image impedance across each of said pairs of terminals.

6. A low-pass wide band amplifier comprising first and second vacuum tubes comprising input and output electrodes having shunt capacitance, a phase-correcting filter network coupled between the output electrodes of said first tube and the input electrodes of said second tube for procuring a phase shift which is a multiple of π at each of one or more preselected frequencies within said band, said filter network including a ladder network having a plurality of inductances in series arms of said network, said inductances comprising at least one pair having negative mutual inductance therebetween, said filter network elements having inherent capacitance included as shunt arms, the output circuit capacitance of said one of said tubes being included in one of said shunt arms and the input circuit capacitance of the other of said tubes being included in another of said shunt arms, said inherent capacitances of said network elements comprising substantial portions of the total capacitances of said shunt arms with which they are associated, and the reactive constants of said filter network being so proportioned as to provide constant- k mid-shunt image impedance across each of said circuits.

7. In a low-pass wide band amplifier, first and second vacuum tubes comprising input and output circuits having appreciable capacitances, a phase-correcting filter network coupled between the output circuit of one of said tubes and the input circuit of the other of said tubes for procuring a phase shift which is a multiple of π at each of one or more predetermined frequencies within said band, said filter network including a ladder network having two remotely separated inductances as series arms adjacent to said tubes, a link circuit comprising inductance coupling said inductances to provide a negative mutual inductance therebetween, and shunt arms comprising said capacitances, the reactive constants of said filter network being so proportioned as to provide constant- k mid-shunt image impedance across each of said capacitances.

8. A low-pass phase-correcting filter network for procuring a phase shift of π at a preselected frequency within said band, said filter network including a transformer comprising primary and secondary windings providing negative mutual inductance, shunt capacitance elements for each of said windings comprising a common portion, and input and output pairs of terminals across

the remaining portions of said shunt capacitance elements, the reactive constants of said filter section being so proportioned as to provide constant- k mid-shunt image impedance across each 5 of said pairs of terminals.

9. A low-pass phase-correcting filter network for procuring a predetermined phase shift which is a multiple of π at each of one or more pre-selected frequencies within the pass band comprising, a ladder network including a plurality of inductances as series arms, at least one pair of said inductances having negative mutual inductance therebetween, a plurality of capacitance elements as shunt arms, and input and output 10 pairs of terminals across different ones of said shunt arms, the reactive constants of said filter network being so proportioned as to present constant- k mid-shunt image impedance across each 15 of said pairs of terminals.

20 10. A low-pass phase-correcting filter network for procuring a predetermined phase shift which is a multiple of π at a preselected frequency within the pass band comprising, two constant- k half-sections with adjacent mid-series terminations, an m -derived filter section interposed between said half-sections, said m -derived section having a value of m greater than unity, and input and output pairs of terminals across said 25 half-sections, wherefore said network presents constant- k image impedance across each of said 30 pairs of terminals.

11. A low-pass phase-correcting filter network for procuring a predetermined phase shift which is a multiple of π at each of one or more pre-selected frequencies within the pass band com- 33

prising, a ladder network including a plurality of inductances as series arms, at least one pair of said inductances having negative mutual inductance therebetween, a plurality of capacitance elements as shunt arms, and input and output 5 pairs of terminals across different ones of said shunt arms, the reactive constants of said filter network being so proportioned as to provide a phase-frequency characteristic which is convex upwardly over the major portion of the pass band 10 and to present constant- k image impedance across each of said pairs of terminals.

12. A low-pass phase-correcting filter network for procuring a predetermined phase shift which is a multiple of π at each of one or more pre-selected frequencies within the pass band comprising, a ladder network including a plurality of inductances as series arms, at least one pair of said inductances having negative mutual inductance therebetween, and a plurality of capacitance elements as shunt arms, and input and output 15 terminals across different ones of said shunt arms, said filter having a maximum phase angle of $n\pi$ and having $n-1$ critical frequencies 20 within the band, the spacing between the critical frequencies being uniform to provide nearly 25 linear phase-frequency characteristic over the fraction

$$\frac{2n-2}{2n-1}$$

30

of the pass band and to present constant- k mid-shunt image impedance across each of said pairs of terminals.

HAROLD A. WHEELER. 35
